UNITED STATES PATENT OFFICE

FRANCIS M. CASE, OF CLEVELAND HEIGHTS, OHIO, ASSIGNOR TO SOLOMON GUGGENHEIM, OF CLEVELAND HEIGHTS, OHIO

IRONING MACHINE

Application filed October 31, 1927. Serial No. 230,153.

This invention relates to ironing machines and particularly to the flat work type utilizing a heated roll and padded pressure rolls.

In ironing machines utilizing the heated rolls and padded pressure rolls, it has been customary to heat the heated roll by steam or gas flame, and in the latter arrangement it is necessary to have a burner of the type which will produce a multiplicity of small flames impinging the inner wall of the roll throughout its length. When this heated roll is of any considerable size, it is also necessary to increase the number of burners and space them in a group at the upper and inner peripheral portion of the roll to further increase the heating effect upon this roll. It is necessary, of course, to vent the products of combustion from this roll and this may only be done through one or both ends of the roll with the result that any practical venting structure must need be limited, and when so limited, the ability to heat the roll by means of gas flames is also limited. It is one object of this invention, therefore, to overcome the above difficulty by producing an artificial venting of the roll to relieve it of its undesirable products of combustion, enhance combustion, and permit the supplying of the roll with ample heating means. In the present instance this is accomplished by a suction device made effective within the roll by a perforated pipe extending throughout the length of the roll at the most critical point so that the roll is relieved of its undesirable products of combustion and the machine as a whole is thereby given greater efficiency in operation.

It is also a feature of this invention to provide the padded pressure rollers with suitable mechanism for exerting uniform pressure upon the work and with means for raising and lowering them into operative and inoperative positions. This same means also functions to connect and disconnect the drive to these rollers from a suitable source.

Another feature of this invention is the provision of suitable thermostatic means for controlling the fuel and thereby controlling the effective temperature of the ironing roll.

Still another feature of the invention is the

construction and arrangement of the ironing roll and its supporting bearings shown, for example, in the drawings at one end of the roll whereby a substantially full sized opening is provided at the end of the roll to furnish the greatest possible vent therefor and also to furnish the greatest possible clearance at this point for access to the inside of the roll, the foregoing being accomplished by the arrangement of the bearing upon the outside of the trunnion sleeve which is as near as possible the size of the bore of the roll. This enlarged opening at the end of the roll makes it possible to substitute other heating means such as an electrical heating unit for the gas burners when they are undesirable.

Other details will be brought out in connection with the following description, drawings and claims.

In the drawings, Fig. 1 is a front elevation of the machine; Fig. 2 is a similar view with parts broken away and in section; Fig. 3 is a right end view; Fig. 4 is a detail view of the safety guard latch; Fig. 5 is an elevation of the left end of the upper part of the machine, as shown in Fig. 1; Fig. 6 is a somewhat diagrammatic view showing the arrangement of the pressure rolls, the heated roll, and the support for the burners and the exhaust tube, with the preferred relation indicated; Fig. 7 is a detail section through the thermostatic control and gas valve; Fig. 8 is a detail through one of the plungers for the pressure rollers; Fig. 9 is a view of a part of the machine as illustrated in Fig. 2, to indicate the machine as equipped with an electrical heating unit; and Fig. 10 is a more or less diagrammatic cross section of the heating roller with the electrical heating element applied.

In the drawings, 1 and 2 represent the main end frame members connected by suitable transverse bars 3 to form a rigid upstanding base frame. The upper ends of these frame members 1 and 2 are provided with frame pads 4 upon which the ironing machine unit rests. The ironing machine unit comprises unit frame members 5 and 6, the latter extending upward and being provided with a main trunnion bearing 7 adapted to receive

the hollow trunnion 8 forming a part of the end head 9 of the ironing roll 10. The body of this ironing roll is of tubular form suitably secured to the end heads. Secured to 5 the end head 9 within the trunnion bearing 7 is a roll driving gear 11 meshing with a driving pinion 12 mounted upon a shaft 13 carrying a worm wheel 14 driven by a worm 15 upon a shaft 16 extending to the front of the 10 machine, where it receives a fast driving pulley 17 and a slow driving pulley 18, these two pulleys being loose upon the shaft and being clutched thereto by any suitable mechanism comprising a shiftable clutch member 15 19 carrying clutch pins 20 on either side thereof, and adapted to be moved longitudinally by a shifting rod 21 telescoped within the hollow end 22 of the shaft 16. This rod 21 is manipulated by a handle 23. The two 20 pulleys 17 and 18 are driven by suitable belts connected to suitably sized driving pulleys 24 and 25 driven by a motor 26 secured in any suitable manner in the frame. By manipulating the clutch, the ironing roll and any 25 parts in driving relation therewith may be driven at various speeds, depending upon the particular pulley ratios of the drive.

The other frame member 5 is of somewhat similar structure except that in place of the 30 main bearing 7, it is provided with an enlarged opening as shown at 27 for providing access to the end of the ironing roll, as will appear. To support the end of the ironing roll at this particular end of the 35 machine, the unit frame member 5 is provided with two circumferentially spaced supporting rollers 28 as shown in Figs. 2 and 5. These rollers engage a trunnion sleeve 29 forming a part of the end head 30 secured to 40 the ironing roll body or tube 10. The trunnion sleeve 29 is preferably made as large as practical so as to provide as great an opening in the end of the roll as possible for venting the roll of as much of the products of combustion as possible, and also for providing 45 access to the roll for various parts of the burner and exhaust equipment.

It is obvious from the foregoing that the ironing roll is supported at both ends with 50 a trunnion bearing fit at the right end, as shown in Fig. 2, and with a trunnion sleeve and external roll mounting at the left end, and these bearings are so arranged that the roll when heated may expand freely to the 55 left or over the rollers 28, and this movement is utilized for regulating the heat, as will appear.

The ironing roll is heated by suitable heating apparatus in the form of burners and it 60 comprises a suitable air mixer 31 at the right hand end, as shown in Fig. 2, mounted upon the upper end of a fuel supply pipe 32 carrying an angle valve 33. This supply pipe is supported in the frame in any suitable 65 manner and supports the burner mechanism

at this trunnion end of the machine. The mixer 31 is provided with a mixer pipe 34 extending through the hollow trunnion 8 into the roll and to a suitable point where it may effectively supply a portion of the burners. 70 At its inner end it is connected to a suitable manifold spider 35 comprising, in the instance shown, three radiating arms 36, 37 and 38, on the outer ends of each of which there is a split collar clamp comprising an arm 75 member 39 and a cap 40 adapted to be clamped together by suitable bolts 41. Each of these clamps receives a burner pipe or tube 42 having an opening 43 communicating with the opening of one of the hollow arms 36, 37, 38, 80 whereby the burner tube is supplied with gas. Each one of the group of arms 36, 37 and 38, is provided with a burner tube and each burner tube is provided with suitable jet openings 44 arranged to project their flames toward the inner peripheral wall of the ironing roll for heating the same. The outer free ends of these burner tubes are plugged as at 45.

In a similar manner the left hand end of 90 the machine as shown in Fig. 2 is provided with a fuel supply, and in this arrangement the mixer 46 is supported in a suitable stepped circular frame member 47 secured to the unit frame member 5. This mixer is provided 95 with a suitable jet 48 connected by an angle valve 49 to a supply line 50. The mixer is also connected to a mixer tube or pipe 51 extending into the roll and connected to a spider similar to the spider 35. In this way, 100 the burner tubes are supplied with gas at a plurality of points and ample fuel is furnished for the heating operation.

The pipes 32 and 50 are connected together and lead to a main control thermostatic valve 105 body 52, Fig. 7, supported in a suitable bracket 53 secured to the frame and having an outlet chamber 54 and an inlet chamber 55 separated by a partition wall 56 providing a valve seat 57. This valve seat is engaged 110 by valve 58, normally forced toward its seat by a spring 59. The valve 58 is provided with a stem 59' adapted to engage in a suitable seat in a thrust screw 60 threaded into a clevis 61 swivelled to the end of a lever 62 fulcrumed 115 at 63 and having an extending arm 64 engaging a thrust screw 65 supported in a plunger 66 slidably mounted in the frame and carrying a roller 67 adapted to engage the circular end edge of the trunnion sleeve 120 29. The lever 62 is normally pressed against an adjustable stop 68 by a spring 69 mounted in the frame so that the adjusting screw 60 is normally held in engagement with the valve stem 59, as clearly 125 shown in Fig. 7.

From the foregoing arrangement of the fuel control, it will be seen that as the ironing roll becomes heated and expands it will tend, by end thrust, to move the plunger 66 130

and the lever 62, in a counter-clockwise direction and allow the gas valve 58 to seat and cut down or shut off the fuel supply, and contrariwise, as the ironing roll cools down, the 5 reverse action will take place and additional fuel will be supplied to the burners.

It is to be borne in mind that a machine of this type may be, and in fact is, arranged to handle articles of considerable size, requiring the ironing to be of considerable length 10 and of some considerable diameter. To heat such a roll considerable fuel must be supplied to the roll and this necessitates some means to handle the excessive volume of the products 15 of combustion which obviously result from the burning of so much fuel within the roll. To accomplish this result a suitable exhaust is provided for the roll and it is in the form of a pipe 70 connected to an exhaust fan or blower 20 70a and extending up through a suitable opening in the member 47 and through the opening 27 in the unit frame member 5. On the interior of the ironing roll this pipe extends throughout the length of the roll and 25 is provided with suitable openings 71 for exhausting the products of combustion from the roll. It is preferable to arrange this exhaust pipe at a point where collection of the products of combustion is most aggravating, 30 and the arrangement shown in Fig. 6 has been found to be extremely practical. In this arrangement the pipe 70 is supported by suitable brackets 72 mounted on the spider 35, as shown. In this arrangement the ironing roll revolves in a clockwise direction and the 35 exhaust pipe 70 is arranged between burners 2 and 3. By the use of this exhaust for the products of combustion ample air for supporting combustion is drawn into the roll 40 and the flames from the burners are permitted to impinge nicely against the inner wall of the ironing wall. It has been found in practice that this exhaust for the products of combustion is so effective that when the 45 exhaust is cut off the flames smother out for considerable distance and, indeed, sometimes go entirely out, but when the exhaust is turned on the burners light up and proper heating proceeds.

50 Cooperating with the ironing roll are suitable pressure rolls, and their construction and arrangement will now be described. At the right hand end of the machine, as shown in Fig. 2, the outer cylindrical portion of the trunnion bearing 7 receives rollers 73 arranged between it and a cam operating ring 74 provided with an outwardly extending fin 75 carrying a plurality of cam members 76, each having a tangential cam slot portion 77 and a dwell at the outer end as at 78. There are three of these cams, one for each group of pressure rollers, as will appear.

At the opposite end of the machine the step 55 conical bracket member 47 is in like manner

provided with a cam ring 79 having a fin 80 carrying similar cams 81.

These cam members at the two ends of the machine form pairs and each pair, one at one end of the machine and one at the other, is adapted by its camming action to move the pressure rollers radially into and out of pressing relation with the ironing roll and there are two rolls moved by each pair of cams, and since there are six rolls shown and their construction and arrangement is identical, a description of one pair of rolls with its mounting and its connection to the cams will suffice for all.

In the case of the right hand end of the machine, the unit frame member 6 is provided with a guide member 82, Fig. 8, secured to the frame in any suitable manner and having a bore or opening 83 extending radially with respect to the axis of the ironing roll. This bore or opening 83 receives a plunger guide 84 provided with a lateral pin 85 projecting through a slot 86 in the guide 82. This pin receives a roller 87 engaging in the cam slot of the associated cam of the group of cams 90 76 and 81. The roller has an operating fit in the cam slot and when the cam is moved bodily by its cam ring the roller will be moved along the tangential portion of the slot and to the dwell, when the plunger guide 95 will be moved outward. This operation moves the pressure rollers away from the ironing rolls, as will appear.

To return the pressure roll to ironing position, the cam rings are rotated in the opposite direction, when the roller 87 will move down the slots of the cams and the padded roll will rest upon the ironing roll. As before intimated, there is a complete roll raising and lowering device at the end of each of the pairs of pressure rollers.

Suitable mechanism is provided for moving the cam rings 74 and 79 and it comprises an ear 88 on each ring, a link 89 pivotally connected to each ear, and an operating lever 90 mounted upon a shaft 91. Each of the arms 90 is provided with an actuating arm 92 extending upwardly at the front of the machine when the pressure rolls are in engagement with the ironing roll, and these arms are connected by an operating bar 93. To raise the rolls this bar is pulled forward to the dotted line position shown in Fig. 3, when the pressure rolls will be moved out of engagement with the ironing roll and the 110 work. In the arrangement just described, the levers 90 and the links 89 are constructed and arranged to provide a toggle arrangement between the shaft 91 and the ears 88 so that when the bar 93 is moved to the rear, as 115 shown in Fig. 3, the cam rings 74 and 79 are rotated and the pressure rollers are drawn with the pressure toward the ironing roll, the toggles finally straightening and locking them in this position.

Each of the plunger guides 84 has a reduced shank 94 surrounded by a tension spring 95 adapted to thrust against an adjusting hand wheel 96 at the outer end, and the inner end against a guide sleeve 97 loosely surrounding the shank 94 and carrying a pair of bearings 98, one arranged on each side of the sleeve 97. The loose fit of the sleeve 97 upon the shank 94 serves to permit the springs 95 to adjust their tension equally upon the two rolls with which they cooperate and apply them with uniform pressure upon the ironing roll. Like bearings at opposite ends of the machine carry the trunnions 99 and 100 of one of the pressure rolls 101. Each of these pressure rolls is provided with a suitable padding 102. Within the sleeves 97 and at the right hand end of the machine each of the trunnions 99 is provided with a driving pinion 103 adapted to mesh with the ironing roll driving gear 11 when the pressure rolls are lowered into engagement with the ironing roll, but free of said gear when the pressure rolls are moved outward.

The machine may be provided with side apron mechanism, and in such an arrangement suitably supported brackets 104 are provided, one at each end of the machine, and these brackets carry a forward feed apron roller 105 supported in bearings 106 carried by guide rods 107 supported in space guides 108. The guide rod 107 is provided with a thrust collar 109 engaged by a spring 110 arranged between it and one of the guides 108 to force the bearings 106 outward to take up the slack in the feed apron. At the entrance between the first pressure roll and the ironing roll is a pair of feed roll bearings 111, one at each end of the machine, and these support a rear feeding roller 112 adapted to engage in a bight of the feed apron 113 preferably made up of a plurality of narrow aprons or endless belts. Within the bearings 111 the roll is provided with a driving gear 114 meshing with a gear 115 secured to the trunnion 100 of the forward-most pressure roll.

In use, when the machine is cold and idle, the pressure rolls are raised from the ironing roll in the manner already described and the operator starts the machine by first turning on the gas by means of the valves 33 and 49 and lights the burners within the ironing roll, the motor having been started so that the ironing roll revolves about the burners and becomes uniformly heated throughout its length and around its circumference. As it becomes heated it necessarily expands, and when its heat is sufficient to produce the proper amount of expansion, the fuel is shut down by the thermostatic valve already described. After the roll has been heated to the proper degree, the operator then throws the pressure rolls and the feed apron into op-

eration by shifting the bar 93 from the position shown in dotted lines to that shown in full lines in Fig. 3, when the various pinions of the several pressure rolls will be brought into mesh with the gear 11 and the rolls will be driven. This also brings about a proper driving mesh of the driving gears of the feed apron, and it will be set in motion. The ironing operation proceeds until the rolls are again released.

If desirable, the machine may be provided with a safety device in the form of a swinging frame comprising end members 116 pivoted to suitable supports 117 secured to the frame. These end members are jointed by suitable rails 118 which are hung by the end members just in front of the entrance between the ironing roll and the first pressure roll. One of the end members, preferably the left one, shown in Fig. 1, is provided with a laterally extending pin 119, shown in Fig. 4, and this pin engages a notch 120 in a latch lever 121 mounted upon a shaft 122. This shaft is supported in a suitable bracket 123 and has a finger 124 thereon adapted to engage a button 125 of any suitable self-opening electric switch arranged in a suitable box 126. This switch is in the motor circuit, and when held in by the finger 124 as shown in Fig. 4, the circuit to the motor is closed but when the latch arm 121 is released from the pin 119 this self-opening switch will break the circuit and stop the motor.

In the modification shown in Figs. 9 and 10, the hollow ironing roll is provided with heating means other than gas burners and in this arrangement the step frame member 47 receives a collar 125 supporting one end of a frame 126 extending within and throughout the length of the ironing roll to the opposite end where it is supported loosely in a suitable opening in a plate 127 secured to the end edge of the trunnion bearing 7 by suitable bolts 128. This frame 126 within the roll supports suitable brackets 129 in turn supporting an electrical heating element 130 of any preferred construction.

When the machine is equipped with an electric heating element, as just described, the parts in the way at the left hand end of the machine, as shown in Fig. 2, are removed and the heating element is inserted within the ironing roller with the end of the heating element frame engaged in the plate 127. The parts at the left end of the machine are then reassembled so that the stepped frame member 47 engages about the ring 125 and supports the heating element. Suitable leads for the heating element 130 may pass through the ring 125.

This application has been divided as to the subject matter of the drive and the support for the ironing roll and these features form the subject matter of the applicant's co-pend-

ing divisional case, Serial No. 311,631, filed October 10, 1928.

What I claim is:

1. In an ironing machine, a frame, a hollow ironing roll mounted for rotation therein and having a vent at the end open to the atmosphere, fuel burners arranged within said roll to heat the same, and means within said roll for withdrawing the products of combustion from said roll.
2. An ironing machine as in claim 1, wherein the ironing roll is provided with an exhaust pipe extending within the roll and adapted to exhaust the products of combustion therefrom.
3. In an ironing machine, a frame, a hollow ironing roll, a plurality of elongated burners extending the length of said roll and arranged in a group near its top, an exhaust pipe extending into said roll near its top and adjacent said burners for withdrawing the products of combustion from said roll, and a suction device connected to said exhaust pipe.
4. In an ironing machine, a frame, a hollow ironing roll mounting for rotation therein, fuel burners arranged within said roll to heat the same, and means within said roll extending the full length thereof for withdrawing the products of combustion therefrom.

In testimony whereof I hereby affix my signature.

FRANCIS M. CASE.
